UNITED STATES PATENT OFFICE

120,875

DESIGN FOR A COMBINED ADVERTISING AND VENDING DEVICE

Abraham N. Spánel, New York, N. Y.

Application April 3, 1940, Serial No. 91,436

Term of patent 14 years

To all whom it may concern:

Be it known that I, Abraham N. Spánel, a citizen of the United States and a resident of New York, New York, whose post office address is 1100 Park Avenue, in the city, county, and State of New York, have invented a new, original, and ornamental Design for a Combined Advertising and Vending Device, of which the following is a specification, reference being had to the accompanying drawing, forming part thereof, wherein the figure is a perspective view of a combined advertising and vending device showing my new design.

I claim:

The ornamental design for a combined advertising and vending device, as shown.

ABRAHAM N. SPÁNEL.
